(57) **CLAIM**

The ornamental design for a drum beater, as shown and described.

DESCRIPTION

FIG. 1 is a rear, right, top isometric view of a drum beater showing our new design;

FIG. 2 is a rear, left, top isometric view thereof;

FIG. 3 is a left, front, top isometric view thereof;

FIG. 4 is a front, right isometric view thereof;

FIG. 5 is a rear, right, bottom isometric view thereof;

FIG. 6 is a rear, left, bottom isometric view thereof;

FIG. 7 is a left, front, bottom isometric view thereof;

FIG. 8 is a front, right, bottom isometric view thereof;

FIG. 9 is a left elevation view thereof;

FIG. 10 is a right elevation view thereof;

FIG. 11 is a top view thereof;

FIG. 12 is a bottom view thereof;

FIG. 13 is a front side elevation view thereof; and,

FIG. 14 is a rear side elevation view thereof.
